LIQUID FUEL BURNING APPARATUS

Marc Resek, Cleveland Heights, Ohio, assignor to
Perfection Stove Company, Cleveland, Ohio, a
corporation of Ohio

Application March 13, 1943, Serial No. 479,037

4 Claims. (Cl. 158—37)

1

This invention relates to improvements in liquid fuel burners of the pot type, its general purpose being to better adapt burners of this character to use on conveyances; and it had its conception in the development of the heating apparatus that constitutes the subject matter of my application Serial No. 479,038, filed concurrently herewith.

The apparatus disclosed in the above mentioned application is intended primarily for installation on military motor vehicles, such as trucks and tanks, for warming the internal combustion engines thereof in cold weather to facilitate starting. Accordingly, the apparatus is used only when the vehicle is standing, and it frequently happens that vehicles of the class referred to are parked on unlevel ground. It is the prime object of the present invention, therefore, to provide a pot type burner that will operate safely and satisfactorily when tilted at considerable of an angle to the horizontal, as well as when level.

A more specific object of the invention is the production of a pot type burner in which the bottom portion of the pot or bowl is so constructed as to provide a sump of less area than said bottom portion and to which the liquid fuel is fed and wherein it is confined when the burner is tilted within practical limits as, for example, up to 7° from the horizontal; and a further object is to include in such a construction, overflow means through which excess liquid fuel may be carried away and beyond the danger point of ignition from the burner in the event of abnormal tilting and a consequent spilling over of a considerable amount of the fuel from the sump into the adjoining portion of the bowl.

It may be explained that the apparatus, when used as an engine heater on motor vehicles, as above set forth, is desirably supplied with fuel from the same source as the engine. When, under these conditions, a highly volatile liquid fuel is employed, the vapors generated therefrom will readily diffuse throughout the bowl. However, in the event that heavier fuel oils are used it is desirable to transfer some of the liquid fuel from the sump to the adjacent portion of the bowl, and it is a further object of the invention to provide means for this purpose, desirably in the nature of a wick siphon.

A still further object of the invention is to increase vaporization of the fuel by providing means additional to the usual metal burner parts for conducting heat to and diffusing it through

2

the fuel in the bottom of the bowl, parts of my improved construction serving this purpose.

Other objects will appear as I proceed to describe the present preferred embodiment of the invention by reference to the accompanying drawings wherein Fig. 1 is a central vertical section through the lower portion of a heating apparatus, similar to that disclosed in the above identified application, incorporating my present improvements; Fig. 2 is a horizontal section through the burner bowl on the line 2—2 of Fig. 1; Figs. 3 and 4 are sectional details on the lines 3—3 of Fig. 2, and 4—4 of Fig. 3, respectively; Fig. 5 is a diagrammatic view including the liquid fuel supply and the burner bowl and showing the same as though the apparatus were tilted perceptibly in a direction away from the fuel supply means, and Fig. 6 is a diagrammatic representation of a modification of the invention.

The burner bowl, designated generally by the reference numeral 1, is located within a casing 2 in spaced relation to the walls thereof. The casing is separated into a combustion chamber 3 and an air compartment 4 by a transverse partition 5 having a central opening 6 that is surrounded by a depending flange 7.

By means of a suitable number of tie-and-spacer elements 10, the bowl 1 is suspended and properly spaced from the partition 5. The reduced upper and lower ends of said elements project through openings in the partition 5 and the top wall 11 of the burner bowl and are suitably connected to said parts, as by welding. Said top wall 11 has a central opening 12 in axial alignment with and somewhat larger than the previously mentioned opening 6 and is surrounded by a depending flange 13. An annular slot 15 is thus provided between the flanges 7 and 13 through which secondary air is admitted to the burner bowl from the aforesaid air compartment 4.

According to the embodiment shown, which, as above stated, is taken from the previously mentioned application, a liquid circulating unit, designated generally by the reference numeral 16, is situated in the combustion chamber 3, and any condensate dripping therefrom is prevented from reaching the interior of the burner bowl by a ring-like condensate arrester 17 that is mounted on the partition 5 about the opening 6.

The peripheral wall of the burner bowl 1 is provided with three circumferential series of air admitting openings, those of the upper series being designated 20, and those of the intermediate 55 and lower series, 21 and 22, respectively. The

peripheral wall of the bowl merges at its lower end into an inwardly curved bottom wall 23 which, in turn, joins a reentrant frusto conical wall 24. A lighting tube 25 has its upper end fitted within a central opening of the frusto conical wall 24 and is shown as extending slightly above said wall, the parts being secured together, as by welding. The tube 25 extends some distance below the bottom plane of the bowl and is surrounded in about said plane by a plate 26 that is fastened, by welding or otherwise, to the bottom wall of the bowl. The lower end of the lighting tube 25 is provided with an outwardly extending flange 28, and a closure 29 is sustained in operative relation to the lower end of the lighting tube by a member 30, shown in the form of a channel, that is hingedly connected to the burner bowl structure and releasably supported in a horizontal position below the lighting tube as set out in detail in the before mentioned application. A loose connection between the closure 29 and the member 30 is provided by a pin 31 which has its upper end riveted or otherwise secured to the closure and passes freely through an opening in the web of the member 30, beyond which it is provided with a head 32. A helical spring 33 surrounds the pin 31 and is compressed between the web of the member 30 and the closure 29 for urging the closure in a direction to engage the flange 28 of the lighting tube 25. By means of an adjustable shim 35 that is pivotally attached to the closure, the latter may be spaced different distances from the flange 28, thereby to admit air in variable controlled quantity through the lighting tube to the interior of the burner, should conditions require.

To prevent chilling of the lower portion of the burner bowl by cold air entering the open bottom of the compartment 4, such as would unduly retard vaporization of the fuel in the bottom portion of the bowl, a shell 38 is applied to the lower end of the bowl and is sustained in spaced relation thereto by a suitable number of L-shaped brackets 39 that are carried by and extend inwardly from the casing 2.

A sump 40 is set off within the annular trough-like bottom of the bowl by dams 42 and 43. Each dam consists of a plate fitted radially within the bottom of the bowl and having its upper edge in about the plane of the upper end of the lighting tube 25. A flange 44 of each dam 42 and 43 is secured, as by spot welding, to the peripheral wall of the bowl, while the edge portion of the dam, downwardly and inwardly beyond the flange, is sealed to the bottom wall 23 and the frusto conical wall 24 by suitable means, such as silver solder. Extending through vertically aligned openings in the bottom wall 23, plate 26 and shell 38, opposite the sump 40, is an overflow pipe 46, the same being suitably sealed within the opening of the bottom wall of the bowl. The top of the pipe is in approximately the plane of the upper edges of the dams 42 and 43, while its lower end is well below the bottom of the bowl. To prevent air entering the bowl through the overflow pipe in sufficient amount to adversely affect operation of the burner, a baffle 47 is supported in slightly spaced relation to the top of the pipe.

Liquid fuel is supplied to the bowl through a tubular connection 50 from a fuel feed chamber 51 which, in turn, is supplied from a float chamber 52 that is connected with the former chamber by an element 53 having a fuel port 54 and a vent port 55. The float chamber with its appurtenances may be of any approved type.

the structure shown including a fuel inlet fitting 56 that is mounted on the top wall 57 of the float chamber and the feed orifice 58 of which is controlled by a needle point valve 59. A float 60 is carried by an arm 61 that is pivotally supported at 62 from a convenient part of the float chamber. A helical spring 63 is interposed between the float arm 61 and the valve 59. Through the intervention of this spring the valve is seated when the float is lifted by an accumulation of fuel within the chamber 52 to the elevation shown in the drawings. Communicatively connected to the fitting 56 is a fuel supply pipe 65, shown as equipped with a valve 66.

Returning to the fuel feed chamber 51, a partition 70 extends from side to side of the same and rises from the bottom thereof to an elevation considerably above the liquid level maintained in the float chamber and divides the fuel feed chamber into a receiving compartment 71, to which fuel flows through the aforesaid port 54, and a delivery compartment 72 wherewith the previously mentioned connection 50 communicates. Supported by a carrier 75 astride the partition 70 is an inverted U-shaped wick 76 which, by capillary and siphonic action, transfers fuel from the receiving compartment 71 to the delivery compartment 72. Incorporated in and extending laterally from the upper end of the carrier 75 is an arm 77 that is swiveled to the top end of a wick adjusting screw 78 that carries a nut assembly 79 with respect to which the screw may be fed up or down by turning the screw in one direction or the other, the screw having a head 80 for such purpose. A spring 82 surrounds the screw 78 and is interposed between the head 80 and an abutment provided by a bushing that surrounds the screw adjacent the bottom of the chamber 51. The spring 82 serves to depress the screw so as to lower the wick a distance permitted by the engagement of the nut assembly 79 with the top of a sleeve 83 that surrounds said screw and rises from the bottom of the chamber 51 to an elevation a suitable distance above the possible maximum fuel level in the delivery compartment 72. The nut assembly 79 has a lateral extension that cooperates with a guide 85 on the side of the chamber 51 in such manner as to prevent the nut assembly from turning. It is apparent from the construction just described that the wick 76 may be adjusted vertically of the partition 70 by turning the screw 78 so as to feed the screw up or down through the nut assembly. This adjustment is for the purpose of changing the rate of fuel feed from the receiving compartment 71 to the delivery compartment 72, and the rate of feed is indicated by indicia on a cylinder 86, that is suitably fastened to the head 80 of the screw, and which indicia may be read in conjunction with the lower edge of a skirt 87 on the bottom of the chamber 51 as an index. With the wick adjusted to obtain the desired rate of feed, the fuel will flow by gravity from the delivery compartment 72 through the connection 50 to the sump 40. While, for the present purpose, it is assumed that the burner is in operation and that the fuel is being consumed at the rate at which it is being fed, it may be explained that, if the burner were not in operation, the fuel would accumulate within the delivery compartment 72 and the sump to the same level as that prevailing in the receiving compartment 71 and float chamber 52.

When the lighter and more volatile hydrocarbons are employed as fuel, such, for example,

as the grades of gasoline used in the engines of vehicles of the class hereinbefore mentioned, the vapors generated from the liquid fuel in the sump 40 readily diffuse throughout the lower portion of the bowl. However, when the heavier fuel oils are used it is desirable to provide means for transferring a part of the liquid fuel from the sump to the adjacent bottom part of the bowl. Such means may consist of an inverted U-shaped wick 90, shown as engaged over one of the dams—dam 43 in the present arrangement—and which is fastened thereto by a clip 81. The wick is desirably of such length that its ends may rest on or near the bottom wall of the bowl on opposite sides of the dam. By this means, when the burner is either level, or is tilted within practical limits, liquid fuel will be transferred by capillary and siphonic action from the sump 40 to the adjoining bottom portion of the bowl, and when the bowl is tilted as aforesaid, the liquid fuel, by reason of the fact that it is divided into two bodies, will not accumulate in either the sump or the adjoining part of the bowl in sufficient amount to overflow. In the case of abnormal tilting, however, the excess fuel will escape through the overflow pipe 46.

To light the burner, the closure 29 is dropped and a lighted torch or the like is projected upwardly through the lighting tube 25 and held in igniting relation to the fuel in the sump 40. Upon withdrawal of the torch, the closure 29 is returned to its former position, and, as combustion progresses, the burner parts become heated. As a consequence, vapors are generated from the fuel in the sump, this action being enhanced by the presence of the dams 42 and 43 which increase the heat conducting capacity of the burner parts. The vapors thus generated will mix with primary air entering through the openings 20, 21 and 22, thereby to produce a combustible mixture which, upon reaching the upper portion of the bowl will commingle with secondary air entering through the slot 15. The resultant highly combustible mixture will burn vigorously in the region of the upper portion of the bowl and in the combustion chamber 3. When the wick 76 is adjusted to feed the fuel at a relatively high rate, so that a large volume of combustible vapors is produced, secondary air in sufficient amount to support combustion under these conditions may be admitted through the lighting tube 25 by adjusting the shim 35 to space the closure 29 more or less from the flange 28. A small amount of air will also enter the bowl through the overflow pipe 46, and will be deflected toward the center of the bowl by the baffle 41.

Throughout the above discussion it has been assumed that the apparatus, if tilted at all, is tilted generally toward the side opposite the fuel supply. If, on the other hand, the apparatus is tilted toward the other side, i. e. the side on which the fuel supply is located, the burner will be robbed of fuel and will burn with a low fire, or not at all, depending upon the angle to which it is tilted.

When the apparatus is approximately level and is in operation, a small amount of fuel will be present in the sump 40, the amount being dependent upon two factors, namely, the rate of fuel feed and the rate of combustion. It will be obvious from a consideration of the foregoing that if the apparatus be tilted within practical limits in the general direction opposite the fuel supply there will be no pronounced increase in the amount of fuel in the sump nor danger of the

fuel overflowing either or both of the dams 42 and 43. The vapors generated from the body of fuel in the sump, whether the apparatus be level or tilted, will diffuse throughout the interior of the bowl and, mixing with the primary and secondary air, burn in normal fashion. In case the apparatus is tilted in the direction aforesaid to such a degree that the liquid fuel overflows from the sump 40 into the adjoining bottom portion of the bowl, the excess fuel will be carried off through the overflow pipe 46 and thus be prevented from attaining the elevation of and from spilling through the openings 22 on the low side of the bowl. Even under these undesirable extreme conditions the apparatus may continue to function, the liquid fuel that escapes through the overflow pipe being carried beyond the danger point of ignition from the combustion occurring inside the bowl and in the combustion chamber.

The purpose of the diagram of Fig. 5 is to indicate what happens when the apparatus is tilted perceptibly in a direction away from the liquid fuel supply means, the angle of tilt being indicated by the relationship of the dot-and-dash vertical line *a* and the inclined dotted line *b*. When the apparatus is in operation and the fuel is being consumed, the liquid level in the delivery compartment 12 of the fuel feed chamber 51, and likewise in the sump 40, is some distance below the liquid level in the receiving compartment 71 and in the float chamber 52, the rate of consumption of the fuel and the rate of fuel transfer over the partition 70 by the wick 76 being the factors responsible for this condition. In this connection it will be noted that, in the illustration, the wick 76 is in its lowest position and consequently functions to transfer the fuel at the highest rate. Elevation of the wick would create a greater difference between the levels of the fuel in the two compartments of the fuel feed chamber. The dot-and-dash line *c* in Fig. 5 represents a projection of the liquid level in the sump and, as will be noted, it is well above the row of air admitting openings 22 and considerably higher than the top of the overflow pipe 46. Consequently, under these conditions, if it were not for my improvements, the burner would overflow through said openings. As it is, the burner will function normally when tilted within practical limits, the volume of combustion depending upon the extent and direction of tilt. The vapors that are generated from the fuel in the sump will diffuse throughout the interior of the bowl and combustion will proceed in the manner already described. The presence of the overflow pipe 46 insures against a dangerous condition in case of extreme tilting, the pipe carrying the fuel beyond where it would be liable to be ignited from the burner. It is understood, however, that, even with this safeguard, such a condition should be rectified immediately upon its being discovered.

The modification diagrammatically illustrated in Fig. 6 includes a cup-like sump 92 that is located substantially centrally within the burner bowl 93 and communicates, through a conduit 94 with the liquid fuel supply means which may be identical with that hereinbefore described. In this construction, the overflow level of the sump 70 92 may be above the plane of the lowest of the air admitting openings in the peripheral wall of the bowl 93. The bowl, on the side opposite the fuel supply means is provided with an overflow pipe 95, the overflow level of which is somewhat below the plane of the lowest of the air admit-

ting openings. In this form of the invention, the fuel in the sump may be lighted from above, as by a torch or other igniting means inserted through an opening or door in the wall of the combustion chamber, as will be readily understood.

Having thus described my invention, what I claim is:

1. In liquid fuel burning apparatus, a burner of the pot type comprising a bowl so constructed that its lower portion forms an annular trough, the peripheral wall of the bowl being provided above said trough with air admitting means, dams disposed across the trough adjacent one side of the bowl and in spaced relation to each other thereby to provide a sump, liquid fuel supply means in fixed relation to the bowl and located adjacent the side thereof aforesaid, communicative connections between said supply means and the burner for conveying fuel to the bowl exclusively through the sump, means maintaining a substantially constant quantity of liquid fuel in said supply means, the surface of said fuel being in a plane considerably below the top of the dams when the apparatus is level, and a U-shaped wick engaged over and suitably attached to one of the dams with its ends adjacent the bottom of the bowl.

2. In liquid fuel burning apparatus of a kind subjected to tilting in the course of its intended use, a burner bowl having air admitting means spaced above the bottom thereof and constructed to provide a relatively deep sump within the bowl contiguous to, and of lesser area than, the bottom of the bowl, the top of the sump being below the top of the bowl and being wide open and in unobstructed communication with the interior of the bowl; liquid fuel supply means in fixed relation to the bowl and located adjacent one side thereof, the aforesaid sump being spaced a substantial distance inwardly from the opposite side of the bowl, communicative connections between said supply means and the apparatus for conveying fuel to the bowl exclusively through said sump, means maintaining a substantially constant quantity of liquid fuel in said supply means, the surface of said fuel being in a plane considerably below the top of the sump when the apparatus is level whereby the apparatus may be tilted perceptibly toward the side opposite the fuel supply means without the sump overflowing into the adjacent bottom portion of the bowl, and overflow means for said adjacent bottom portion contiguous to the side of the apparatus remote from the fuel supply means for carrying off excess fuel in the case of extreme tilting of the apparatus, the overflow level of the last mentioned means being such as will define a possible maximum liquid level in said bottom portion below the aforesaid air admitting means.

3. In liquid fuel burning apparatus of the kind subjected to tilting in the course of its intended use, a burner bowl constructed to provide a relatively deep sump within the bowl contiguous to, and of lesser area than, the bottom of the bowl, the top of said sump being below the top of the bowl and being wide open and in unobstructed communication with the interior of the bowl;

liquid fuel supply means in fixed relation to the bowl and located adjacent one side thereof, the aforesaid sump being spaced a substantial distance inwardly from the opposite side of the bowl, communicative connections between said supply means and the apparatus for conveying fuel to the bowl exclusively through the sump, means maintaining a substantially constant quantity of liquid fuel in said supply means, the surface of said fuel being in a plane considerably below the top of the sump when the apparatus is level, and means having a small conductive capacity for transferring fuel in limited quantity from the sump to the adjacent bottom portion of the bowl.

4. In liquid fuel burning apparatus of a kind subjected to tilting in the course of its intended use, a burner bowl provided with air admitting means spaced a substantial distance above the bottom of the bowl, means comprising a dam setting off a sump within the bowl, the top of which is below the top of the bowl, liquid fuel supply means in fixed relation to the bowl and located adjacent one side thereof, said sump being spaced a substantial distance inwardly from the opposite side of the bowl, communicative connections between said supply means and the apparatus for conveying fuel to the bowl exclusively through the sump, means maintaining a substantially constant quantity of liquid fuel in said supply means, the surface of said fuel being in a plane considerably below the top of the aforesaid dam when the apparatus is level whereby the apparatus may be tilted toward the side opposite the fuel supply means without the fuel overflowing into the adjacent bottom portion of the bowl, an overflow pipe extending through the bottom of the bowl contiguous to the side of the apparatus remote from the fuel supply means and the overflow level of which is below the bottom plane of the aforesaid air admitting means, said overflow pipe serving normally to admit air to the bowl, and a baffle in closely spaced relation to the top of the overflow pipe.
